WIRE RECORDER

Emil C. Steinbach, Chicago, Ill., assignor to
Charles P. Peirce, Evanston, Ill.

Application February 17, 1950, Serial No. 7,979

Term of patent 7 years

(Cl. D26—14)

To all whom it may concern:

Be it known that I, Emil C. Steinbach, a citizen of the United States, residing at Chicago, in the county of Cook and State of Illinois, have invented a new, original, and ornamental Design for Wire Recorder, of which the following is a specification, reference being had to the accompanying drawing, forming a part thereof.

In the drawings:

Figure 1 is a perspective view of a wire recorder, showing my new design;

Figure 2 is a front elevational view of my wire recorder as it appears with the wire magazine removed;

Figure 3 is an end elevational view thereof;

Figure 4 is a plan view thereof; and

Figure 5 is a rear elevational view thereof.

The broken lines are for illustrative purposes only.

I claim:

The ornamental design for a wire recorder, as shown and described.

EMIL C. STEINBACH.
